UNITED STATES PATENT OFFICE.

ALFRED J. ASH, OF BOSTON, MASSACHUSETTS.

NECKTIE-FASTENER.

SPECIFICATION forming part of Letters Patent No. 349,832, dated September 28, 1886.

Application filed February 27, 1886. Serial No. 193,453. (No model.)

To all whom it may concern:

Be it known that I, ALFRED J. ASH, of Boston, in the county of Suffolk and State of Massachusetts, have invented a new and Improved Necktie-Fastener, of which the following is a specification.

This improvement relates to necktie-fasteners which are attached to the backs or shields of neckties and scarfs for the purpose of securing the same to the collar-button; and it is especially advantageous when a turned-down collar is worn.

In the accompanying drawings, in which similar letters of reference indicate like parts, Figure 1 is a rear perspective view of a necktie or scarf with my improved fastener attached. Fig. 2 is a top view of the same in position upon a collar-button. Fig. 3 is a detached perspective view of the device in position upon a collar-button.

My device consists of a single piece of wire bent into the shape shown, so as to spring over the head of the collar-button and confine the necktie in its proper position. The ends of the wire are situated inside the necktie or scarf, between the shield *a* and the body of the scarf *b*. These ends may or may not be soldered or otherwise secured together, as desired. From its ends the two portions *A* of the wire extend up substantially parallel, as shown in Fig. 3, then are bent at right angles, and substantially parallel at *B*, and pass rearward through a suitable opening, *c*, in the shield. The two portions of the wire are then bent down, and substantially parallel with each other for a short distance at *C*, then apart at *D* at an angle of, say, twenty or thirty degrees, then slightly toward each other at *E*, then decidedly apart at *F*, rearward at *G*, and together at *H*, and at *I* form in the center of the wire a loop which is coiled around an eyelet, *d*, placed in the shield, or in any suitable manner securely attached to said shield.

It will readily be perceived that the two portions of the wire between its ends and the loop *I* form springs, so that when the fastener is drawn down upon a collar-button the neck of said button forces the two portions apart

as the shoulders *J* pass the neck, so that when the button has arrived at its proper position 50 in the fastening—viz., in the space *K* between the portions *D* *E* of the wire—it is prevented by the spring thereof from getting out of position.

There has always been difficulty in the use 55 of wire fastenings on neckties in connection with turned-down collars, for the reason that in putting on the necktie or scarf it has first to be tucked under one fold of the collar and then under the other, and in the operation 60 tipped sidewise considerably from a vertical position, and is while tipping sidewise very apt to slip off the collar-button, by reason of the bending or spreading of the wire fastener, which has usually been somewhat in the shape 65 of an inverted *V*. In this device the collar-button is so well confined in the fastening, and the fastening itself, being connected at the bottom, is so strong that both slipping out and spreading are prevented and the difficulty 70 above alluded to is obviated.

Having thus fully described my invention, what I claim, and desire to secure by Letters Patent, is—

1. The hereinbefore-described wire necktie- 75 fastener, consisting, essentially, of the end vertical parallel portions, *A*, horizontal parallel portions *B*, vertical parallel portions *C*, outwardly-bent portions *D*, inwardly-bent portions *E*, outwardly-bent portions *F*, rearwardly-bent portions *G*, horizontal portions *H*, and means whereby the lower portion of the fastener is secured to the shield, substantially as and for the purpose set forth.

2. The hereinbefore-described wire necktie- 85 fastener, consisting of the end vertical parallel portions, *A*, horizontal parallel portions *B*, vertical parallel portions *C*, outwardly-bent portions *D*, inwardly-bent portions *E*, outwardly-bent portions *F*, rearwardly-bent portions *G*, horizontal portions *H*, and loop *I*, all substantially as and for the purpose described.

ALFRED J. ASH.
